UNITED STATES PATENT OFFICE.

ANDREW H. STONE, OF KANSAS CITY, MISSOURI.

COMBINATION LIBRARY AND DINING TABLE.

1,325,454.

Specification of Letters Patent. Patented Dec. 16, 1919.

Application filed May 29, 1916. Serial No. 100,626.

To all whom it may concern:

Be it known that I, ANDREW H. STONE, a citizen of the United States, residing at Kansas City, in the county of Jackson and 5 State of Missouri, have invented certain new and useful Improvements in Combination Library and Dining Tables, of which the following is a specification.

This invention relates to combination 10 library and dining tables and has for its object to produce a structure which can be converted from a library into an extension dining table or vice versa easily and conveniently, and which, in either form, is solid, 15 rigid and substantial, a further object being to produce a convertible table of simple and inexpensive construction.

With the objects named in view the invention consists in certain novel and peculiar 20 features of construction and organization of parts as hereinafter described and claimed, and in order that it may be more fully understood reference is to be had to the accompanying drawings, in which:—

25 Figure 1, is a top plan view of the structure arranged in full lines as a library table and in dotted lines as a dining table, a quarter section of the top being cut away to expose one of the slide extensions of the table-top supporting frame, one of the end extensions of the top and one of the corner wings of said extension.

Fig. 2, is an enlarged central transverse section of the table, on the line II—II of 35 Fig. 3, and also shows the portion which constitutes the entire top of the table when the same is used as a library table, in elevated position in dotted lines.

Fig. 3, is an inverted plan view of the 40 lower edge of the table frame, to clearly show the swiveled stem of the table top, and means for limiting the rotatable movement of said stem, and coöoperating means for raising the stem and locking it in raised or lowered position.

Fig. 4, is a top plan view of the table with the portion constituting the top of the structure when used as a library table extending transversely of the table frame, and one of 50 the slides of said frame extended.

Fig. 5, is a side view of the table with all of the parts in the position which they occupy in Fig. 4, but with one of the table

top extensions and the corresponding corner wings swung from within to a position upon 55 their respective slide extensions.

Fig. 6, is a top plan view of the table with the portion omitted which constitutes the top of the structure when used as a library table, and also showing one of the end extensions 60 and its wings in the position said parts occupy when the structure is used as a dining table.

Fig. 7, is an enlarged section taken on the line VII—VII of Fig. 1, when the structure 65 is arranged as a dining table as shown by dotted lines in said figure.

Fig. 8, is an enlarged section taken on the line VIII—VIII of Fig. 6.

Fig. 9, is a section on an enlarged scale 70 of a part of the table top taken on the line IX—IX of Fig. 6, and Fig. 10 is a perspective view of a corner of the frame.

Referring to the drawings in detail, 1 indicates the stationary sides of the frame of 75 the table, 2 is a central cross piece or bridge secured to said sides, 3 are shallower cross pieces rigidly connecting sides 1 at the ends thereof, said sides and cross pieces constituting a rigid frame.

At opposite sides of the central cross piece the sides 1 are provided on their inner surfaces with longitudinal guide tongues 4, the outer ends of the same overlying the end cross piece 3.

The sides have secured on their lower edges longitudinal beading strips 5, similar beading strips 6 being secured to and projecting outwardly from the lower edge of the cross strips 3. Underlying the central cross piece 2 and occupying the same horizontal plane as the beading strips is a cross strip 7, and also connecting beading strips 5, a short distance inward from beading strips 6 are end cross strips 8. At their outer corners 90 the end cross pieces 3 are provided with vertical openings 9 for receiving upwardly projecting tenons 10 formed at the upper ends of the legs 11 of the table. The end pairs of legs are shown as connected between cross 100 beading 6 and cross strips 8 with cross pieces 12 (see Figs. 6 and 7) and extending downwardly from cross pieces 12 are vertical slats 13 secured at their lower ends to cross piece 14 connecting the legs near the lower ends 105 thereof, and connecting cross pieces 14 is a

longitudinally extending shelf 15. It is to be understood in this connection that the character or form of the support for the frame of the table forms no essential part of 5 this invention and is susceptible of change without affecting the construction and operation of the frame and operative parts hereinafter described.

At each side of the central cross piece 2 and adapted for longitudinal sliding movement between the sides 1 is a rectangular slide extension 16 for the frame described, the outer ends of said extension projecting 10 beyond the sides thereof and having their end extremities beveled as at 17, so that when the slide extensions are in closed position said beveled ends shall abut against the ends of the sides 1 and fit snugly in recesses 18, formed in the end extremities of said sides 15 20 25 30 35 40 45 50 55 60 65 70 75 80 85 90 95 100 105 110 115 120 125 130 135 140 145 150 155 160 37, a clamping screw 38 extending up into the pin and bearing against one leg of the staple to hold the same firmly in position.

Arranged under the cross strip 7 is a lever 39 fitting loosely around the swiveled pin between the legs of the staple, and said lever extends loosely through and fulcrums on a bracket 40 secured to cross strip 7. It also extends through a bracket 41 depending from said cross strip 7, said bracket 41 having an arm 42 projecting from one of its sides at an intermediate point thereof so that the lever may overlie said arm or underlie it, it being understood that the slot 15 or opening of both brackets exceeds the width of the lever to allow for sufficient lateral adjustment of the latter to move it from a position above to a position below said arm. To clamp and lock the top section 28 in the position shown by full lines Figs. 1 and 2, the outer end of the lever is pressed upward and then swung to the right to cause it to overlie the arm 42 of bracket 41. When it is desired to raise and secure 25 the top section 28 in the position shown by Figs. 4 and 5, the lever is swung to the left from over arm 42 to unlock it. Pressure is then applied to cause it to fulcrum on bracket 40 and assume the position shown by dotted lines Fig. 2, and full lines Fig. 5, the lever being then swung to the right to cause it to underlie arm 42, as shown in Fig. 5, and thus support the top in its elevated position, and while thus elevated it can be swung from the 35 position shown by full lines Fig. 2 to the position shown by dotted lines same figure and full lines Figs. 4 and 5, or from the last named position to the position shown by full lines Fig. 2. To limit the rotatable movement of said top section to a quarter revolution a pair of stops 43 and 44 are secured to and depend from cross strip 7, the staple 37 engaging stop 43 when the top section occupies the position shown by full lines, 40 Fig. 2, and the stop 44 when said top section occupies the position shown by full lines, Fig. 4.

The top section 28 must be raised not only to permit it to be rotated but also to permit 50 of the adjustment of the slide extensions and of the withdrawal from the slide extensions of the table top extensions comprising the central sections 45 and the wings 46 thereof. Normally the central top extensions 45 lie 55 snugly within and upon the bottom strips 20 and 21 of the slide extensions respectively, and are invisible when the structure is in the form of a library table as will be readily seen by reference to Fig. 1. It will be 60 noticed that the wings 46 at such time are folded inwardly and lie upon the central sections 45 with their inner or straight edges flush with the straight side edges of section 45, and that said flush edges are hingedly 65 connected. The hinged connections are such

that when the wings are swung outwardly they assume the horizontal plane of section 45 with their said straight edges abutting securely together. There are a plurality of hinges for each wing, and each preferably 70 consists of a link 47 fitting and pivoted at its opposite ends in U-shaped members or brackets 48, one of such members being inset in the side edges of section 45 and the other in the adjacent straight edge of the associated wing. 75

Before the wings can be unfolded to the position shown by full lines at the left hand end of Fig. 6, it is necessary to raise the sections 45 out of the slide extensions 80 and to permit of this operation and yet retain the sections 45 in permanent connection with their respective slide extensions, U-shaped rocker bars pivotally link sections 45 to their respective slide extensions. The 85 bridge portions 49 of said rocker bars extend through transverse grooves 50 in the underside of sections 45 near the inner edges of the latter and are retained therein by bearing caps 51 (see Fig. 7). The sides or 90 arms 52 of the rocker bars occupy the spaces between the side edges of sections 45 and the sides of the slide extensions, and terminate in outwardly projecting ends 53 extending through and pivoted in the sides of 95 the slide extensions, as shown most clearly at the right hand end of Fig. 5; it being noticed in this connection that when the sections 45 fit within the slide extensions as shown clearly in Figs. 1 and 4, the bearing caps 51 depend into the openings 22, of the bottom strips 20 and 21 of the slide extensions, this accommodation of said bearing caps permitting the sections 45 to lie flatly upon said bottom strips. 100

When it is desired to withdraw the sections 45 from the slide extensions, the operator thrusts his fingers upwardly through the space between the bottom strips 20 and 21 of a slide extension and thus raises the 110 outer end of the overlying section 45 to enable him to grasp the outer edge of the same above the outer end or cross piece of said slide extension. He then pulls outwardly thereon and thus causes the section 45 and its folded wings to swing from within the slide extension to the position shown at the right hand ends of Figs. 5 and 6, where it will be noticed the section 45 rests upon the outer end or cross piece of the slide extension, it being also noticed by reference to Fig. 7, that the outward movement of the section 45 is limited through the abutment of the arm 52 of the rocker bar 49 against the downwardly and inwardly sloping edges 115 of stop blocks 54 secured to the inner surfaces of the sides of the slide extensions. 120

After the sections 45 have been withdrawn from within the slide extensions, the wings can be unfolded, but before this operation 130

can be properly performed certain braces must be preliminarily adjusted, as said braces in their folded or inoperative positions prevent the complete unfolding of the 5 wings. In this connection it will be noticed that the wings are provided with recesses 46^a for receiving the rocker bars at the junction of their bridge portions and arms, when the wings are unfolded, these recesses being 10 necessary because the rocker bars are set in the top extensions 45 and the wings correspond in thickness to said extensions 45 and abut squarely against the side edges of the latter, when unfolded. The above mentioned braces comprise transverse rods 55 for engagement when folded with transverse grooves 56 in the underside of wings 46. One end of each brace terminates in a pivoted arm 57 pivotally engaging the wing 20 and a pivot-retaining plate 58, secured to the underside of said wing. The outer end of the brace terminates in a hook 59 which when the wing is folded and the companion section 45 is within the slide extension, ex- 25 tends downwardly between the inner or straight edge of the wing and the adjacent side of the associated slide extension. When the associated section 45 occupies the position shown in Fig. 5, the hook-end of said 30 brace must be raised to permit the wing to be fully unfolded as well as to permit said brace to be swung inwardly and upwardly until its hook-end 59 engages an opening 60 formed in the adjacent bottom 35 strip of the slide extension, as shown clearly in Fig. 8, the contiguous side of the slide extension being diagonally grooved as at 61 to accommodate the inclined brace, as also shown in the last named figure.

40 Assuming that the table section 28 has been raised, that the slide extensions have been drawn outward until arrested by the contact of stops 25 with turn buttons 27, that the top section 28 has then been turned 45 90 degrees to extend transversely across the frame, that the extension sections 45 have been withdrawn from the slide extensions, and that the wings have been unfolded and secured by the braces in the position shown 50 by full lines at the left hand end of Fig. 6, the operator completes the conversion of the structure into a dining table as follows: He manipulates the lever 39 to effect the lowering of the top section 28 and the locking of 55 the same in its new position, and in this connection it will be noted that the sides 1 are provided with recesses 62 to receive the side portions of the beads 29 so that the top may rest flatly upon sides 1. Pressure is then 60 applied to move the slide extensions inwardly until arrested by the abutment of the inner edges of the sections 45 and the unfolded sections 46, against the opposing edges of the section 28, it being noticed that 65 the inner edges of section 45 and wings are

rabbeted as at 63 and 64 respectively in order to coöperate with the rabbeted or beaded edges of section 28 in producing a step joint connection as shown clearly in Fig. 7, it being also noticed by reference to the last 70 named figure that the braces 55 at such time are outward of the ends of the frame and thus do not interfere with the inward adjustment of their respective slide extensions by abutment against the ends of the frame. 75 The slide extensions are locked in engagement with the section 28 by causing the turn buttons to engage the notches 26 in the inner edges of the bottom strips 20 of said slide extensions. 80

When the parts are thus arranged the dining table is complete and the movable parts are so solidly connected and braced that the table can be pushed about a room by applying force against any part of it, 85 it being noted that the tongue and groove connection between the slide extensions and the stationary sides 1 of the frame insure rigidity as regards up and down movement of said slide extensions, and that the wings 90 and the adjustment of the inner edges of the sections 45 against section 28 coöperate in guarding against upward swinging movement of the former and the wings, and that the latter are prevented from swinging 95 downward by said braces and by resting upon the upper edges of the sides and outer cross pieces or ends of the slide extensions and by the hinges connecting said wings with the interposed sections 45. 100

The operations above described as necessary to convert the structure into a dining table are reversed to reconvert such table into a library table, it being noted in this connection and by reference to Figs. 1 and 105 4, that when the top extensions 45 and folded wings are within the slide extensions, the depending or hook ends of the braces 55 are disposed beyond the outer ends of the stops 54 and hence may be folded completely 110 within the grooves 56 in said wings.

For library purposes it is desirable that the table be equipped with drawers 65, the same extending slidably through one of the sides 1, and each rests upon the cross strips 115 7 and 8 below the slide extensions, the drawers being provided at their front or exposed ends with handles or buttons 66 by which to manipulate them, one of said drawers being shown as partly withdrawn or opened, 120 in Fig. 6.

From the above description it will be apparent that I have produced a device of the character outlined, embodying the features of advantage enumerated as desirable 125 in the statement of the object of the invention, and while I have illustrated and described the preferred embodiment of the invention, it will be apparent that it is susceptible of modification in minor particu- 130

lars without departing from the principle of construction involved or sacrificing any of the advantages of the appended claims.

I claim:—

5. 1. In a convertible table, stationary sides having opposite recesses in their upper edges, slide extensions supported by and between the sides and provided with outer cross pieces to fit between and abut the ends 10 of the sides when the slide extensions are closed, a vertically-adjustable rotatable top provided with depending side beads to lie outward of said sides and depending end beads to lie outward of said cross pieces, 15 when the latter abut the ends of said sides, said side beads being adapted to depend into the said recesses after the top is adjusted to extend crosswise of the said sides, means to clamp the said top in the last 20 named position or in the position it occupies when the side beads and end beads respectively lie outward of said sides and cross pieces, extensions for said top secured to and resting on said slide extensions and 25 abutting against the side edges of said top when in its transverse position, means to lock the said slide extensions with the table top extensions abutting the side edges of the said adjustable top, said table top extensions 30 each comprising a central portion and wings hinged to and flanking the same when in unfolded position and resting on the same when in folded position, and braces pivoted to said wings at their undersides and engaging and underlying said slide extensions to secure the wings in their unfolded positions.
2. In a convertible table, a slide extension comprising parallel sides, cross pieces 40 connecting the sides, and spaced bottom strips connecting the cross pieces, a foldable table top extension adapted when folded to rest in the slide extension and upon the bottom strips thereof and when unfolded upon 45 the outer cross pieces and sides of the slide extension, and consisting of a central section and two wings hinged thereto to lie when folded upon said central section and when unfolded in the same horizontal plane 50 as and abut the side edges of the latter, a U-shaped rocker bar having its bridge portion pivoted to said central section of the extension and having the free ends of its arms pivoted in the sides of the slide extension 55 and stop braces secured to the inner surfaces of the sides of the slide extension and adapted to serve as a rest for the arms of the U-shaped rocker bar when the table top extension is resting on the outer cross piece and sides of the slide extension.
3. In a convertible table, a slide extension comprising parallel sides, cross pieces connecting the sides, and spaced bottom strips connecting the cross pieces, a foldable table 60 top extension adapted when folded to rest in the slide extension and upon the bottom strips thereof and when unfolded upon the outer cross pieces and sides of the slide extension, and consisting of a central section and two wings hinged thereto to lie when folded upon said central section and when unfolded in the same horizontal plane as and abut the side edges of the latter, a U-shaped rocker bar having its bridge portion pivoted to said central section of the extension and having the free ends of its arms pivoted in the sides of the slide extension and stop braces secured to the inner surfaces of the sides of the slide extension and adapted to serve as a rest for the arms of the U-shaped rocker bar when the table top extension is resting on the outer cross pieces and sides of the slide extension.
4. In a convertible table, a chambered slide extension, a foldable table top extension adapted when folded to rest in the slide extension and when unfolded upon the top of said extension, and consisting of a central section and two wings hinged thereto to lie when folded upon said central section and when unfolded in the same horizontal plane as and abut the side edges of the latter, a U-shaped rocker bar having its bridge portion pivoted to said central section of the extension and having the free ends of its arms pivoted in the sides of the slide extension, and braces pivoted to said wings and lying within the slide extension when the top extension is folded and resting on said bottom strips, and extending downward and inward from the wings and engaging the slide extension when the top extension is unfolded to secure the wings against folding movement.
5. In a convertible table, a chambered slide extension, a foldable table top extension adapted when folded to rest in the slide extension and when unfolded upon the top of said extension, and consisting of a central section and two wings hinged thereto to lie when folded upon said central section and when unfolded in the same horizontal plane as and abut the side edges of the latter, a U-shaped rocker bar having its bridge portion pivoted to said central section of the extension and having the free ends of its arms pivoted in the sides of the slide extension, and means rigid with the slide extension for serving as a rest for the arms of the said rocker bar when the table top extension is unfolded and resting on top of the slide extension.
6. In a convertible table, a chambered slide extension, a foldable table top extension adapted when folded to rest in the slide extension and when unfolded upon the top of said extension, and consisting of a central section and two wings hinged thereto to lie when folded upon said central section and when unfolded in the same horizontal plane as and abut the side edges of the latter, swinging means connecting the central section of the table top extension with the slide extension for causing the inner end of the former to describe an upward and outward arc when said table top extension is grasped and pulled upward and outward, and means for arresting the outward movement of the table top extension when the latter is resting on the top of said slide extension.
7. In a convertible table, a chambered slide extension, a foldable table top extension adapted when folded to rest in the slide extension and when unfolded upon the top of said extension, and consisting of a central section and two wings hinged thereto to lie when folded upon said central section and when unfolded in the same horizontal plane as and abut the side edges of the latter, swinging means connecting the central section of the table top extension with the slide extension for causing the inner end of the former to describe an upward and outward arc when said table top extension is grasped and pulled upward and outward, and means for arresting the outward movement of the table top extension when the latter is resting on the top of said slide extension.

- sliding extension and when unfolded upon the top of said extension, and consisting of a central section and two wings hinged thereto to lie when folded upon said central section and when unfolded in the same horizontal plane as and abut the side edges of the latter, swinging means connecting the central section of the table top extension with the slide extension for causing the inner end of the former to describe an upward and outward arc when said table top extension is grasped and pulled upward and outward, and stop braces secured to the slide extension in the path of the said means to arrest the same when the table top extension has been drawn outward and is resting on the top of the said slide extension.
7. In a convertible table, stationary sides, a cross piece connecting the sides midway the ends thereof, provided with a vertical opening, a top having a pin depending through said opening, a lever fulcrumed at an intermediate point and underlying the cross piece and engaging the pin to press the same downward and to swing laterally thereon, and a bracket through which the lever extends with capacity for vertical and lateral movement, said bracket having an arm to underlie or overlie the lever and prevent vertical movement thereof.
8. In a convertible table, stationary sides, a central cross piece connecting the sides midway the ends thereof, end pieces connecting the ends of the sides, a top having a pin depending slidably and rotatably through the center of said first-named cross piece, a staple extending through the lower end of said pin, a pair of stops for engagement by said staple to limit the rotatable movement of the table top to one-fourth of a circle back and forth, and a lever suitably fulcrumed and engaging said staple to apply pressure thereon to raise the pin and top preliminary to rotatable movement
- thereof, and means for engagement by said lever to secure the pin and top in elevated position or to clamp the top down upon the sides.
9. In a convertible table, a slide extension having parallel sides and bottom openings near said sides, a foldable table top extension adapted when folded to rest within the slide extension and when unfolded on top of the slide extension, and consisting of a central section and two wings hinged thereto to lie when folded upon said central section and when unfolded in the same horizontal plane as and abut the side edges of the latter, movable means connecting the central section of the table top extension with the slide extension and limiting outward movement of the former with respect to the latter, and braces pivoted to said wings and adapted to fold down upon the same when the table top extension is folded within the slide extension and to be disposed downwardly and inwardly and fitted at their free ends in the said openings of the slide extension, when said wings are unfolded so as to serve as braces for the latter.
10. In a convertible table, a rectangular frame, a slide extension having a bottom strip provided at one edge with a laterally projecting portion constituting a shoulder and with a recess, and a turn-button pivoted to an end of said frame and adapted to be disposed in the path of said shoulder to limit outward movement of the slide extension or to be disposed in said recess of said strip to lock the slide extension against end-wise movement in either direction.

In testimony whereof I affix my signature, in the presence of two witnesses.

ANDREW H. STONE.
